UNITED STATES PATENT OFFICE.

ADOLPH PETZOLD, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 19,393, dated October 29, 1889.

Application filed August 19, 1889. Serial No. 321,179. Term of patent 3½ years.

To all whom it may concern:

Be it known that I, ADOLPH PETZOLD, a citizen of the United States, and a resident of Philadelphia, Pennsylvania, have invented a new and original Design for Rugs, of which the following is a description, reference being had to the accompanying photographic illustration, making part hereof.

The leading feature of my invention or design is an elongated hollow panel on the groundwork of the rug, the middle open or hollow space resembling, generally, a Gothic arch, the panel proper being ornamented with scroll-work edge ornaments, also with a cap, and the corners and body of it with flowers and leaves. In the open middle space, in practice, I place ornamental figures.

A is the elongated hollow panel; B, the groundwork of the rug; C, the middle hollow or open space; D, the cap-piece. 20

E E are flowers, and F F leaves.

G G are middle ornamental figures.

What I claim is—

The design for rugs, consisting of the open panel A, with a cap-piece D, open space C, producing an interior in the general form of a Gothic arch, ornamental flowers E E, and leaves F F, substantially as shown. 25

ADOLPH PETZOLD.
